UNITED STATES PATENT OFFICE.

HARRISON H. TAYLOR, OF DETROIT, MICHIGAN, ASSIGNOR TO THE MICHIGAN RADIATOR AND IRON MANUFACTURING COMPANY, OF SAME PLACE.

REAMING-MACHINE.

SPECIFICATION forming part of Letters Patent No. 399,352, dated March 12, 1889.

Application filed August 8, 1888. Serial No. 282,274. (No model.)

To all whom it may concern:

Be it known that I, HARRISON H. TAYLOR, a citizen of the United States, residing at Detroit, county of Wayne, State of Michigan, have invented a certain new and useful Improvement in Reaming-Machines; and I declare the following to be a full, clear, and exact description of the invention, such as will enable others skilled in the art to which it applies to make and use the same, reference being had to the accompanying drawings, which form a part of this specification.

My invention has for its object an improved reaming-machine designed and adapted for various uses, and having special utility for reaming the opposite hubs of a radiator-loop simultaneously.

My invention contemplates a machine for reaming both hubs at one end of a radiator-loop, and for reaming the hubs at both ends, if desired. For these purposes my improved machine may thus be constructed either single or double, as may be preferred.

My invention consists of the devices and appliances, together with their combinations and arrangements, as illustrated in the drawings, and more fully hereinafter described, and pointed out in the claims.

In the drawings, Figure 1 is a front elevation. Fig. 2 is a side elevation. Fig. 3 is a plan view of a portion of the machine. Fig. 4 is a vertical cross-section through the machine on the line $x-x$, Fig. 2. Fig. 5 is a front view of the reaming-tool.

I carry out my invention as follows: A represents any suitable supporting bed or table. Where a double machine is used, as illustrated in the drawings, for simultaneously reaming the two ends of a radiator-loop, two supporting-tables A A may be united by suitable connecting-beds, A' A'.

B B are driving-shafts provided with a driving-pulley, B', and suitably journaled upon the beds A A. A pinion, b, upon each driving-shaft, meshes with a gear, C, upon a shaft, C', said shaft being provided toward each extremity with pinions c c', said pinions meshing, respectively, with gears D D' upon the individual reamer-spindles D² D³, the shafts C' and spindles D² D³ being properly journaled upon the beds A A. Said spindles

are each provided with a reamer-tool, d, and constructed to work upon the two opposite hubs of a radiator-loop coincidently.

In a double machine the mechanism above described is simply duplicated to drive each set of reamer-spindles at the two ends of the radiator-loop, as shown. The rotation of each individual reamer-tool is thereby secured. It is necessary, however, to give a reciprocating as well as a rotary movement to the reamer-spindles. Each said spindle is therefore so journaled upon the supporting-table as to have an endwise motion, as more particularly shown in Fig. 4. Toward the outer end each spindle may be screw-threaded and provided with an adjusting-nut, D'. The extreme outer end of the spindle projects through the adjacent boxing a, as shown at d'. A bell-crank lever, E, pivoted to the table, as at a', and provided with a weight, E, is arranged to bear against the nut to retract the reamer-spindle when the work of the reamer-tool is completed. The reamers are forced to the work in the following manner: One of the shafts C' running across the front of the machine is provided with a worm, c², at each extremity, as in Figs. 1 and 4. The shafts D² and the forward shaft, C', are broken off upon the left of the machine in the plan view, Fig. 3, the reciprocating mechanism being shown at one side only. Worm-gears F F', mounted, respectively, upon shafts G G', mesh with each of the worms c².

In a double machine the shafts G G' extend across the machine, as shown upon one side in Fig. 3, being journaled upon each of the supporting-beds A, and provided toward each extremity with cams g g', arranged to bear upon the extremities of the reamer-spindles, as more fully illustrated in Fig. 4. As the cams rotate in the proper direction, the reamer-spindles are crowded forward to their work, and when the end of the spindle rides off the cam the weighted bell-crank E will immediately retract the spindles, withdrawing the reamer-tools from the hubs of the radiator-loops or other work.

Any suitable device may be employed to throw off the driving-belt—as, for instance, one of the driving-shafts B, as shown in Fig. 3, may be provided with a fast and a loose pul-

ley, $b' b^2$. A belt-guide, II , engaged upon a spring-bar, II' , may be arranged to be operated by a lever, II^2 , in the usual manner. Suitable devices for holding the work may also be employed. Thus a bracket, I , may be located upon each bed A , provided with a screw-clamp, I' , and clamping-base I^2 .

The duplicate mechanism for operating the two sets of reamers I prefer to make adjustable, the one to and from the other, so that the same mechanism may be employed with radiator-loops of different lengths. Thus the supporting-beds A A may be adjusted to and from each other by grooving the connecting-beds A' A^2 , as shown at a^3 , one of the supporting-beds having a movable connection therewith, so that it may be set and held in any desired position, as by clamping-bolts a^4 a^5 .

20. Intermediate the beds A A the connecting-beds A' A^2 may be provided with a connecting-bar, A^4 , constructed also to form a supporting-arm, A^5 , upon which a radiator-loop may be engaged. A loop, J J' , is shown in position in Fig. 2.

25. To permit the adjustment of the two beds relative to each other, the shafts G G' may be grooved, as shown in Fig. 3, at g^2 to receive a spline in the cam.

30. A reamer-machine so constructed is evidently very efficient in use, simple and easily operated.

What I claim as my invention is—

1. The combination, with a supporting-bed, 35 of a rotatable and reciprocatory reamer-spindle provided with a reamer-tool, a driving-shaft geared with said spindle, a cam to force the spindle to the work, and a worm-gear to operate the cam, substantially as set forth.

40. 2. In a reaming-machine, the combination, with a supporting-bed, of a driving-shaft geared with a shaft, C' , and a reamer-spindle geared with shaft C' , said spindle having a reciprocatory movement upon said bed, substantially as described.

45. 3. In a reaming-machine, the combination of the supporting-bed and driving-shaft, a shaft C' , geared with the driving-shaft, a reamer-spindle provided with a reaming-tool 50 geared with the shaft C' , said latter shaft provided with a worm, a worm-gear meshing with said worm, and a cam driven by said worm-gear to reciprocate the reamer-spindle, substantially as described.

4. The combination, with a supporting-bed, 55 of a pair of reamer-spindles having a reciprocatory movement thereupon toward and from each other, and a driving-shaft geared with a shaft, C' , said shaft C' geared with the reamer-spindles, substantially as set forth.

5. The combination, with a supporting-bed, 60 of a pair of rotatable reciprocatory reamer-spindles, a driving-shaft geared with said spindles, and a cam-shaft geared with the driving-shaft to force the reamer-spindles respectively to the work, substantially as set forth.

6. The combination, with a supporting-bed, 65 of a pair of retracting reamer-spindles having a rotating and reciprocating engagement upon said bed, of a driving-shaft geared with said spindles, and a cam to feed the spindles forward to their work, substantially as set forth.

7. The combination, with a supporting-bed, 75 of a pair of rotatable and reciprocatory reamer-spindles located end to end to admit the work between them, a driving-shaft geared with said spindles, cam-shafts geared with the driving-shaft to feed the spindles to the work, and an automatic retracting device, substantially 80 as set forth.

8. The combination, with beds A A , of a 85 pair of rotatable and reciprocatory reamer-spindles located upon each bed, said beds having an adjustable connection the one with the other, substantially as described.

9. The combination, with supporting-beds A A , of a pair of reamer-spindles engaged upon each bed, a driving-shaft geared with each pair of spindles, and cam-shafts G G' to feed the spindles to the work, said shafts respectively geared with the driving-shaft, substantially as set forth.

10. The combination, with a supporting-bed, 95 of a rotary and reciprocatory reamer-spindle, a driving-shaft geared with a shaft, C' , feeding mechanism to feed the spindle to the work, said feeding mechanism and spindle geared with said shaft C' , and a retracting device to restore the spindle to its normal position, substantially as described.

In testimony whereof I sign this specification in the presence of two witnesses.

HARRISON H. TAYLOR.
